MEANS FOR SUPPORTING REMOVABLE TYPE UNITS IN TYPEWRITERS

Filed May 17, 1926

2 Sheets-Sheet 2

UNITED STATES PATENT OFFICE.

ARTHUR PATEMAN, OF LEICESTER, ENGLAND, ASSIGNOR TO IMPERIAL TYPEWRITER COMPANY LIMITED, OF NORTH ERVINGTON, LEICESTER, ENGLAND, A BRITISH COMPANY.

MEANS FOR SUPPORTING REMOVABLE TYPE UNITS IN TYPEWRITERS.

Application filed May 17, 1926, Serial No. 109,797, and in Great Britain June 2, 1925.

This invention is for improvements in or relating to typewriters and has reference to the type arranged for interchangeability of the type-unit. Heretofore in such machines it has been necessary, after disconnecting a locking device for locking the unit to the stationary part, to lift the type-unit bodily away from its operative position. This has usually necessitated a certain amount of manoeuvring of the unit clear of obstacles on the stationary part of the machine, and as the unit weighs several pounds the operation is a rather delicate one. The present invention has for its object to provide an improved construction wherein this difficulty is obviated.

According to the present invention, a typewriter of the type referred to above is characterized by the provision of runners or the equivalent on the framework of the machine so arranged as to guide and support the type-unit during its withdrawal from and introduction to the stationary part of the machine.

Preferably, the runners extend in a direction parallel to the sides of the machine. This arrangement enables the unit to be moved into and out of its operative position in a direction which is transverse to the longitudinal axis of the platen roller, which is desirable, as will be readily understood.

The type-unit may be disposed between the runners and supported thereon by means of studs or the equivalent projecting laterally from the unit. This arrangement is advantageous in that the provision of the runners need not incur any additional depth in the framework of the machine.

According to a feature of the invention, the runners may be curved in such manner as automatically to guide the unit clear of the various portions of the stationary part of the machine which otherwise would obstruct the unit in its passage to and from the said operative position.

According to a further feature, the runners may be arranged to support the unit in its operative position and may be mounted on the framework of the machine in such manner, (for example, on eccentric studs) as to be adjustable in a vertical plane for

the purpose of positioning the unit to a nicety in relation to the stationary part of the machine. The adjustability of the runners may compensate for any slight irregularities that may exist between the type-unit that is removed from the machine and the substituted unit. 55

The invention will now be further described with reference to the accompanying drawings, which illustrate a preferred embodiment by way of example, and in which:—

Figure 1 is a sectional elevation taken along the line 1—1 of Figure 2;

Figure 2 is a horizontal section taken 65 along the line 2—2 of Figure 1, and

Figure 3 illustrates in detail the eccentric studs connecting the runners with the framework of the machine.

Like reference numerals indicate like parts 70 in the various figures.

The framework of the machine comprises an upper casting 1 and a lower casting 2. The two castings are bolted together by means of bolts 3. Carried upon the top of the upper casting is a top-plate 4 which is secured by screws 5 to said upper casting. The platen roller is indicated at 6. 75

The type-unit of the machine is indicated diagrammatically and the side-plates of the unit are shown at 7. The unit is arranged to be supported upon and guided by a pair of horizontally disposed runners 8 mounted upon the side walls 9 of the lower casting 2. The runners extend from near the rear wall of the lower casting to a point sufficiently far beyond the front of the stationary part of the machine to enable the unit to be moved outwardly upon the runners far enough to bring it clear of obstructing portions of said stationary part, so that it is only necessary when the unit has been drawn out to the maximum degree on the runners, to lift the unit bodily away. The need for manoeuvring the unit clear of obstructions 85

is thereby obviated. 90

The unit is arranged to be supported upon the upper edge of the runners by means of studs 10 projecting laterally from the side-plates 7 of the units. Two studs 10 are provided at each side of the unit and they are 100 so located in a vertical direction as to result

in the bottom of the unit being substantially flush with the underside of the runners, as shown.

The runners are curved, as illustrated, for the purpose of guiding the unit clear of any portions of the stationary part of the machine which otherwise would obstruct the unit in its travel to and from the operative position. The uppermost projection from the unit is shown at 11 in Figure 1. This projection which is shown purely diagrammatically is the uppermost part of the ribbon carrier which in operation reciprocates in a more or less vertical plane so as to bring the ribbon into and out from an operative position wherein it will be interposed between the platen roller and the type on any one of the type-bars when the type-bar is in its operative position. It will be appreciated of course that the member 11 has no functional connection with the members which directly comprise the invention. The curvature of the guides is such as to result in sufficient lowering of the unit during its withdrawing movement to bring the upper extremity of this projection 11 below the lower edge 12 of the front of the top-plate, as the projection 11 passes said lower edge. The actual curvature of the runners would be made to suit the requirements in any given case. The extreme withdrawn position of the unit is shown in Figure 4.

The runners 8 are carried upon the side walls 9 of the lower casting 2 by means of studs 13, each of which is formed, as shown in Figure 3, with an eccentric 14 adjacent the head. Rotation of any one of the studs 13 will obviously result in slight movement of the runner through which the stud passes, in a vertical plane. Any one of the studs may be rotated so that independent adjustment of either end of either runner is possible. The studs 13 are screwed into a sleeve 15, which is rotatably mounted in a boss 16, formed on the inner face of the side wall 9. The sleeve 15 is provided with a head 17, whereby it may be rotated or held from rotation by the application of a screw-driver, when the adjustment of the stud 13 is effected.

The rear end of each of the runners is formed, as shown, with a V-shaped slot to receive the rear studs 10 on the unit and act therewith as a stop for the unit with a wedging action. The wedging action is advantageous in that it provides for rigidity of the unit in its operative position.

In order to prevent movement of the runners on their adjustable mountings after they have been set, due to backward thrust imparted say by the rearward movement of the unit into its operative position, there are provided in the rear of the framework two set-screws 18 which act as abutments and which can be set so as to abut firmly against

the rear ends of the runners after the latter have been correctly adjusted on their mountings.

The unit is provided with stops at the forward end, each consisting of a stud 19 mounted upon the runners so as to project inwardly therefrom, and a latch 20 pivotally mounted upon the side-plates 7 of the type-unit. The latches are mounted upon the forward supporting studs 10, and they are spring-controlled in a direction to engage the studs 19. The latches are moved in the inoperative direction by means of finger-pieces 21, pivotally connected at 22 to an arm 23 formed on the latch. The latches are formed with a cam 24 which, during the inward movement of the type-unit comes first into contact with the stud 19, and causes the latch to ride over the stud until the end of the notch 25 in the latch reaches a position such that latching can take place.

In order to ensure that the type-unit shall be firmly supported upon the runners without end-play, due, for example, to irregularities between the interchangeable type-units, the stud 19 is eccentrically mounted so as to be adjustable to vary the distance between the stops.

Those elements of the mechanism on the unit which are arranged to come into operative engagement with co-operating elements on the stationary part of the machine are so disposed and arranged as to come into abutting engagement. Such an arrangement of elements is indicated in chain-line in Figure 1. The elements indicated by the numerals 26 and 27 form part of the type-unit and are arranged to abut, in known manner, against cylindrical portions 28 and 29 respectively of co-operating elements 30 and 31 on the stationary part of the machine. It is thus possible to withdraw the type-unit from its operative position without disconnection of any parts other than the latches aforesaid. Also when an automatic latching device is provided, as described above, it is possible to introduce the type-unit into its operative position directly without any manipulation of any element of the mechanism.

I claim:

1. In a typewriter constructed and arranged for interchangeability of the type-unit, the combination with the type-unit of runners on the frame-work of the machine for supporting and at the same time guiding the type-unit as it is withdrawn from and introduced into its operative position in the machine, for the purpose described.
2. In a typewriter constructed and arranged for interchangeability of the type-unit, the combination with the type-unit of runners on the frame-work of the machine for supporting and at the same time guiding the type-unit as it is withdrawn

from and introduced into its operative position in the machine, the runners being disposed at either side of the type-unit so that the latter is carried between the runners, 5 for the purpose described.

3. In a typewriter constructed and arranged for interchangeability of the type-unit, the combination with the type-unit of runners on the frame-work of the machine 10 for supporting and at the same time guiding the type-unit as it is withdrawn from and introduced into its operative position in the machine, the runners being disposed at either side of the type-unit so that the latter is 15 carried between the runners, and studs projecting laterally from the type-unit and constituting the means whereby the latter rests upon the runners, for the purpose described.

4. In a typewriter constructed and arranged for interchangeability of the type-unit, the combination with the type-unit of runners on the frame-work of the machine for supporting and at the same time guiding the type-unit as it is withdrawn from and 25 introduced into its operative position in the machine, said runners being curved in such manner as automatically to guide the type-unit clear of obstructions on the stationary part of the machine, for the purpose described.

5. In a typewriter constructed and arranged for interchangeability of the type-unit, the combination with the type-unit of runners on the frame-work of the machine 35 for supporting and at the same time guiding the type-unit as it is withdrawn from and introduced into its operative position in the machine, the runners being disposed at either side of the type-unit so that the latter is carried between the runners and curved in such manner as automatically to guide the type-unit clear of obstructions on the stationary part of the machine, for the purpose described.

6. In a typewriter constructed and arranged for interchangeability of the type-unit, the combination with the type-unit of runners on the frame-work of the machine for supporting and at the same time 45 guiding the type-unit as it is withdrawn from and introduced into its operative position in the machine, the runners being disposed at either side of the type-unit so that the latter is carried between the runners and curved in such manner as automatically to 50 guide the type-unit clear of obstructions on the stationary part of the machine, and studs projecting laterally from the type-unit and constituting the means whereby the latter rests upon the runners, for the purpose described.

7. In a typewriter constructed and arranged for interchangeability of the type-unit, the combination with the type-unit of 60 runners on the frame work of the machine

for supporting and at the same time guiding the type-unit as it is withdrawn from and introduced into its operative position in the machine, said runners being so mounted upon the frame-work as to be adjustable 70 in a vertical plane, for the purpose described.

8. In a typewriter constructed and arranged for interchangeability of the type-unit, the combination with the type-unit of 75 runners at either side on the frame-work of the machine for supporting and at the same time guiding the type-unit as it is moved to and from its operative position in the machine and means on the type-unit 80 whereby the latter rests upon the runners at four points, two at each side of the unit, the runners being so mounted upon the frame-work of the machine as to be independently adjustable in a vertical plane 85 either by parallel movement in a vertical direction or by angular movement about either end of the runner, for the purpose described.

9. In a typewriter constructed and arranged for interchangeability of the type-unit and comprising the combination of parts referred to in claim 8, the adjusting means for the runners being such that the latter might be displaced by backward thrust of 90 the runners as the type-unit is pushed home, the combination with the runners of stops thereon for limiting the inward movement of the type-unit and adjustable abutments 100 on a stationary part of the machine arranged to project towards the inner end of the runners and engage the same against backward movement due to said thrust.

10. In a typewriter constructed and arranged for interchangeability of the type-unit, the combination with the type-unit of 105 runners on the frame-work of the machine for supporting and at the same time guiding the type-unit as it is withdrawn from and introduced into its operative position in the machine, and stops located respectively near the front and the rear of the type-unit, each consisting of an element on the runner and a cooperating element on the type-unit, for limiting both the inward and the outward 110 movements of the type-unit, one of said stops being adjustable to vary the effective distance between itself and the other stop, for the purpose described.

11. In a typewriter constructed and arranged for interchangeability of the type-unit, the combination with the type-unit of 115 runners on the frame-work of the machine for supporting and at the same time guiding the type-unit as it is withdrawn from and introduced into its operative position in the machine, and stops for limiting both the inward and the outward movement of the type-unit located respectively near the rear and the front of the unit, of which stops those 120 125 130

which limit the inward movement are constituted each by a lateral stud on the unit by which the latter is caused to rest upon the runner, and co-operating therewith, a V-shaped abutment on the inner end of the runner adapted to engage the stud with a wedging action, and those stops which limit the outward movement are adjustable to vary the effective distance between the front 10 and rear stops, for the purpose described.

12. In a typewriter constructed and arranged for interchangeability of the type-unit, the combination with the type-unit of runners on the frame-work of the machine 15 for supporting and at the same time guiding the type-unit as it is withdrawn from and introduced into its operative position in the machine, and stops for limiting both the inward and the outward movement of the type-unit located respectively near the rear and the front of the unit, of which stops those which limit the inward movement are constituted each by a lateral stud on the unit by which the latter is caused to rest upon the 20 runner, and co-operating therewith, a V-shaped abutment on the inner end of the runner adapted to engage the stud with a wedging action, and those stops which limit the outward movement each consist of an eccentrically headed stud mounted in the 25 runner and projecting laterally therefrom and a finger-operated notched latch pivoted to the side of the unit to swing in a vertical plane and engage the head of the stud, yielding controlled towards the stud and cam-shaped to ride, uncontrolled by the fingers, 30 over the head of the stud during the inward movement of the unit until the unit has reached its operative position whereupon the latch will move automatically to its latching position.

13. In a typewriter constructed and arranged for interchangeability of the type-unit, the combination with the type-unit of runners on the frame-work of the machine for supporting and at the same time guiding the type-unit as it is withdrawn from and introduced into its operative position in the machine, and stops for limiting both the inward and the outward movement of the type-unit located respectively near the rear and the front of the unit, of which stops those which limit the inward movement are constituted each by a lateral stud on the unit by which the latter is caused to rest upon the runner, and co-operating therewith, a V-shaped abutment on the inner end of the runner adapted to engage the stud with a wedging action, and those stops which limit the outward movement each consist of an eccentrically headed stud mounted in the runner and projecting laterally therefrom and a finger-operated notched latch pivoted to the side of the unit to swing in a vertical plane and engage the head of the stud, yielding controlled towards the stud and cam-shaped to ride, uncontrolled by the fingers, 45 over the head of the stud during the inward movement of the unit until the unit has reached its operative position whereupon the latch will move automatically to its latching position.

In testimony whereof I affix my signature.

ARTHUR PATEMAN.
